UNITED STATES PATENT OFFICE.

JAMES GARTH MITCHELL, OF BELFAST, IRELAND.

HAND DEVICE FOR BEATING FABRICS AND THE LIKE.

Application filed May 12, 1924. Serial No. 712,767.

To all whom it may concern:

Be it known that I, JAMES GARTH MITCHELL, a subject of the King of Great Britain and Ireland, residing at Belfast, 5 Ireland, have invented certain new and useful Improvements in Hand Devices for Beating Fabrics and the like, of which the following is a specification.

The present invention relates to improvements in hand devices for beating fabrics and the like and the object thereof is to provide an article which will combine more effectively than in previous articles of this kind the desirable quality of flexibility with 15 a certain amount of rigidity.

The various features of the invention will be apparent from the following description taken in conjunction with the accompanying drawings which show the preferred 20 form of the invention.

In the drawings:—

Fig. 1 is an elevation, partly in section, of a device according to the invention;

Fig. 2 is a perspective view of the connector shown in Fig. 1; and

Fig. 3 is a perspective view of a cap which is used to keep the beating members in place.

The handle 1 is bored near its upper end 30 with two passages 2 and 3 which are at right angles to the length of the handle.

From the lower aperture to the upper end of the handle there are, upon each side of the latter, recesses 4 and 5 for a purpose 35 which will appear hereinafter. The device comprises two beating members 6 and 7 which are formed of a covered wire 12, the wire being plain, coiled or crimped and the cover being of such material as rubber, cork 40 or leather, although other materials could be used; preferably the wire is embedded in rubber. A one-piece connector 8 having two apertures 9 and 10 is provided, and there is also a cap 11. This cap is provided with 45 lateral projections 13 which serve to fit closely around the beating members and fix them securely upon the handle.

The pieces of covered wire 6 and 7 are threaded through the apertures 9 and 10 of 50 the connector 8 and through the passages 2 and 3 and the two ends of each wire are then connected together after having been bared for this purpose. The substantially oval loops thus formed are moved until the

joints are within the passages in the handle 55 as shown in Fig. 1 when the loops take up the position indicated in full lines. The cap 11 is then slipped on to the handle and forces the loops towards and partly into the grooves 4 and 5; the loops then take up 60 the position indicated in dotted lines. The cap may be merely held in position by the tendency of the loops to expand or it may be definitely connected to the handle. As will be seen from the drawing the cap is 65 non-circular and the head of the handle is shaped to correspond.

Such a beating device has the advantage that it will not damage the article being beaten as would an ordinary wire beater, 70 it is flexible enough and yet at the same time, owing to the combination of the straight passages and the cap, it has sufficient rigidity to be effective.

It will be observed that there are several 75 advantages in boring the passages 2 and 3 straight through the handle; firstly, the handles can be turned out very cheaply owing to the fact that the two holes can be bored in a single operation, and at most 80 there are only two operations; secondly, the beating members 6 and 7 can be passed straight through the passages, which simplifies the assembling; thirdly, the sharp bend between the part of the beating member 85 within the passage and the part bent upwards within the cap gives the device a firmness and takes away the flabby effect that would otherwise be felt in beating. An advantage of the one-piece connector is that 90 the number of pieces is a minimum, and that time occupied in assembling is reduced to a minimum as the beating members have merely to be threaded through the connectors. 95

Having now fully described my invention what I claim and desire to secure by Letters Patent is:—

A hand device for beating fabrics and the like comprising a handle having substantially straight transverse passages extending therethrough; covered wire beating members of oval form, having the ends of the wire members twisted together and disposed in the transverse passages so that the wire is 105 braced and protected thereby.

In testimony whereof I affix my signature.
JAMES GARTH MITCHELL.
